UNITED STATES PATENT OFFICE

151,273

DESIGN FOR A TABLE TYPE REFRIGERATOR

Edward A. Kirchhof, Altadena, Calif.

Application September 23, 1946, Serial No. 133,497

Term of patent 3½ years

(Cl. D67—3)

To all whom it may concern:

Be it known that I, Edward A. Kirchhof, a citizen of the United States, residing at Altadena, in the county of Los Angeles and State of California, have invented a new, original, and ornamental Design for Table Type Refrigerator, of which the following is a specification, reference being had to the accompanying drawing, forming part thereof.

Figure 1 is a perspective view of a table type refrigerator, showing my new design.

Figure 2 is a top plan of the same.

Figure 3 is a front elevation of the same.

Figure 4 is an end elevation of the same.

I claim:

The ornamental design for a table type refrigerator, as shown.

EDWARD A. KIRCHHOF.
